LOOSE LEAF BINDER

James C. Dawson, Webster Groves, Mo., assignor
to Elma N. Dawson, Webster Groves, Mo.

Application January 12, 1934, Serial No. 706,397

4 Claims. (Cl. 129—24)

The invention relates to the so-called wire arch type of binders, in which the mating sheet-carrying prongs are mounted on toggle wires which are housed within a spring plate.

5 As these metal parts have heretofore been made, the end pairs of prongs are carried at the ends of the toggle wires, and it has been difficult to apply booster levers to such devices because the ends of the spring plate extend a considerable 10 distance beyond the ends of the wires, and the load end of the lever has consequently been longer than the power end.

The object of the present invention is to provide for an extension of the wires approximately 15 to the ends of the plate, and to so shape their end portions that they may be engaged by the booster lever.

An embodiment of the invention is hereinafter described, and is illustrated in the accompanying 20 drawing, in which

Fig. 1 is a view in perspective of the completed metal;

Figs. 2 and 3 are sectional views on the lines 25 2—2 and 3—3, respectively, of Fig. 1; and

Fig. 4 is a view in perspective of the booster lever and an end of the spring plate, the parts being unassembled.

The spring plate 10 is, generally, of ordinary 30 form, being transversely arched and having in-turned margins or flanges, as shown at 11, and being apertured, as shown at 12, to accommodate the leaf-holding arch prongs 13. These prongs are, as usual, carried by a pair of toggle wires 14, which are pivotally engaged within the marginal 35 portions 11 of the plate. The leaf-carrying arches may be as many in number as desired, three being shown. The prongs 13 of all of these arches are attached to the toggle wires, preferably by welding.

40 Intermediate of each pair of arches the wires 14 are arched inwardly, as shown at 15, 16, the apexes of the arches pivotally engaging as a toggle joint, as shown at 17. The end portions 18, 19, of the wires 14 are prolonged beyond the 45 end arches, extending approximately to the ends of the plate 10, and the extreme ends of these wires are turned inwardly, as shown at 20, 21, and approximately meet at the center line of the

50 metal and together form a bearing bar for engagement by the load end 22 of a booster lever 23. The plate 10 is formed of a blank, the end portions 24 of which are prolonged beyond the marginal portions which constitute the flanges 11, and are turned downwardly to close the ends of the 55

metal. This flap 24 is centrally apertured, the recess extending beyond the line of fold.

The booster lever 23 is L-shaped, and is housed within the end portion of the plate 10, its power end being laterally notched, as shown at 25, 25, to receive the side margins of the recess in the plate end 24 and be thereby permanently held in operative position. Force being applied to tilt the power end of the lever backwardly, it fulcrums against the upper portion of the plate end 24, its toe 22 exerting upward pressure upon the ends 20 and 21 of the toggle wires, the upper margins of the notches 25 continuing to ride on the upper face of the arch while the lever moves the necessary distance to spread the prongs 13.

15 The load end of the lever being L-shaped and its lateral arm being downwardly inclined, as shown in Fig. 3, the initial movement of the lever has a cam action beneath the inturned ends, 20, 21 of the wires; and as the movement continues the leverage increases, the load end of the lever being in effect progressively shortened up to the time the toggle arms pass center.

25 The described construction provides for the use of a short toggle lever of ample power, and it furthermore provides for the accommodation of an attaching rivet which may be entered through the aperture 26 in the plate 10, and located between the end arch and the end of the plate.

The term "metal" as here used is the trade 30 name for the metal parts, of various forms, of loose leaf binders.

I claim as my invention—

1. A loose leaf metal comprising a spring arch plate, a pair of prong-carrying wires in pivotal engagement with the marginal portions of the plate and having toggle engagement intermediate of their ends, the ends of the wires extending approximately to the ends of the plate and being turned inwardly, a booster lever fulcrumed on one end of the plate and engaging the corresponding inturned ends of the wires, and sheet-carrying prongs carried by the wires.

2. A loose leaf metal comprising a spring arch plate having inturned margins, a pair of prong-carrying wires pivotally engaging the inturned margins of the plate and being arched inwardly for toggle engagement, sheet-carrying prongs fixed to the wires, the wires being prolonged beyond such prongs and approximately to the ends of the plate and having their ends inturned, and booster levers pivotally mounted on the end portions of the plate and engaging under such in-turned ends.

3. A loose leaf metal comprising a spring arch 55

plate having an end of the arch extending downwardly and vertically and centrally slotted, the slot extending into the arch, a booster lever of greater width than the slot and having marginal recesses for receiving the edges of the slot, toggle wires pivotally engaging the margins of the plate and having their ends inturned to overlie the load end of the lever, and sheet-carrying arches mounted on the wires intermediate of their ends.

4. A loose leaf metal comprising a spring arch

plate having the ends of the arch extending downwardly and vertically and centrally slotted, the slots extending into the arch, a booster lever at each end of the plate of greater width than the slot and having marginal recesses for receiving the edges of the slot, toggle wires pivotally engaging the margins of the plate and having their ends inturned to overlie the load end of the levers, and sheet-carrying arches mounted on the wires intermediate of their ends.

5

JAMES C. DAWSON.
